CIRCUIT BREAKER

Peter Piffath, Elmhurst, N. Y.

Application October 26, 1933, Serial No. 695,244

15 Claims. (Cl. 200—76)

This invention relates to circuit breakers and more especially to generator cut-outs for automobile battery charging systems.

An object of this invention is an efficient and inexpensive circuit breaker having provision for establishing positive non-chattering engagement between the movable and stationary contacts.

In a circuit breaker embodying the invention, the movable contact is carried by a resilient member bowed to establish a condition of bias with respect to the stationary contact. Means are provided for impressing stresses on the movable contact carrying member tending to move the contact member out of its normal position.

Such movement is opposed by the contact carrying member until the stresses overcome the resistance of said member, whereupon the movable contact is snapped into positive non-chattering engagement with the stationary contact. The extent of movement of the movable contact is such that its carrying member retains this condition of bias so that upon release from the stresses, the movable contact member is returned to normal position.

Other objects, novel features and advantages of this invention will be apparent from the following specification and accompanying drawing, wherein:

Fig. 1 is a side elevation showing the cut-out mounted on a generator;

Fig. 2 is an enlarged vertical section;

Fig. 3 is a plan view;

Fig. 4 is a bottom view;

Figs. 5 and 6 are enlarged fragmentary sections corresponding generally to Fig. 2;

Fig. 7 is a perspective view of the armature and armature spring, and

Fig. 8 is a circuit diagram.

A metal base 10 is provided with legs 11 which rest on the casing of the generator G and are attached thereto by bolts 12. A U-shaped metal frame 13 has its bottom portion lying on an insulating plate 14 which in turn rests on the base 10. An electro-magnet is arranged within the frame 13 and has an iron core 15 terminating in a threaded stud 16 of reduced diameter and passing through apertures in the bottom of the frame 13, the insulator 14 and the base 10. The stud 16 fits snugly in the aperture in the insulator 14, but the apertures in the frame 13 and the base 10 are of larger diameter than the stud. Insulators 17 and 18 surround the stud 16 and insulate it from the frame 13 and base 10. The core 15 is provided with an enlarged head 19. Insulating discs 20 surround the core

15, the upper one engaging the head 19 and the lower one engaging the insulator 17 which in turn is engaged by the shoulder formed between the core 15 and the stud 16. A coil 21 of fine insulated wire surrounds the core 15 and a coil 22 of coarse insulated wire surrounds the coil 21.

A portion of one side of the U-frame 13 is struck out and bent down to form a contact member 23 which extends through an aperture 10 in the insulator 14 and through an opening in the base 10, the latter opening being of such size that the contact member does not touch the base. A second contact member 24 is riveted to the insulator 14 and the base 10 is cut 15 away to provide an opening to receive the end of the contact member 24, the opening being of such dimensions that the contact member does not touch the base.

One end 22a of the coil 22 extends through the bottom insulator 20, the bottom of the frame 13, the insulator 14 and the contact member 24 to which it is attached, the opening through the frame 13 being of sufficient size that the wire does not touch the frame. The other end 22b 25 of the coil 22 is attached to a collar 25 carried by the stud 16.

One end 21a of the coil 21 extends through the bottom insulator 20, the bottom of the frame 13 from which it is insulated, the insulator 14, 30 the base 10 from which it is also insulated and is connected by means of the screw 26 to the contact member 23. The other end 21b of the coil 21 is connected to the base 10 at 27. A nut 28 is threaded on to the end of the stud 16 35 to clamp the various parts in assembled relation.

The upper ends of the frame 13 are bent to form flanges 29. A spring plate 30 rests on the flanges 29 and its ends are bent to form loops fitting around the flanges 29. The plate is cut 40 away to form a pair of inwardly extending tongues 31 connected by strips 32 offset from the tongues on opposite sides thereof and merging with the tongues centrally thereof. A cross member 33 extends between the strips 32, intermediate the free ends of the tongues 31. The armature 34 of the electro-magnet is of rectangular shape and is supported by rivets 35 located at the inner ends of the tongues 31. A contact 36 is riveted to the cross member 33 45 and is arranged in an aperture in the armature 34. A contact 37 is provided on the cap 19 of the core 15 to cooperate with the contact 36. The strips 32 are bowed up slightly centrally (see Fig. 5). The armature is provided with 50 55

lugs 34a which are adapted to engage the top insulator 20 to limit downward movement of the armature.

Normally, the armature and contact stand in the position shown in Fig. 5 with the contact 36 spaced from the contact 37 and the strips 32 biased away from the head 19. Energization of the electro-magnet causes the armature to be pulled down to the position shown in Fig. 6. As the armature moves down, the inner ends of the tongues 31 are pulled down, thus applying stresses to the strips 32 tending to move the contact 36 toward the contact 37, such movement being initially opposed by the resistances exerted by the upward bow of the strips. However, after the armature has moved down a predetermined distance, the stresses exerted on the strips 32 through the tongues 31 overcome the resistance of the bow portions and the contact 36 snaps down into engagement with the contact 37. A quick positive non-chattering engagement of the contacts 36 and 37 is obtained.

The design and arrangement is such that with the contact 36 in engagement with the contact 37, the strips 32 retain their condition of bias away from the head 19 so that as soon as the electro-magnet is de-energized the contact 37 returns to its original position.

The contact member 23 is connected to the generator and the contact member 24 is connected to the battery. With the generator at rest, the contact 36 is spaced from the contact 37 and the circuit between the generator and battery is broken, thus preventing discharge of the battery through the generator. When the generator is started up, current flows by way of contact member 23 through the high resistance coil 21 and base 10 to ground, thereby energizing the electro-magnet to draw down the armature and move the contact 36 into engagement with the contact 37. Such engagement closes a circuit from the generator to the battery through the contact member 23, U-shaped member 13, plate 30, contact 36, contact 37, core 15, collar 25, low resistance coil 22 and contact member 24, by which charging current is supplied to the battery. Upon closing of this circuit, the flow of current through the high resistance coil 21 becomes negligible but the electro-magnet is kept energized by the coil 22 and the armature is maintained in its pulled-down position. This condition persists until the generator stops, whereupon current ceases to flow through the coil 22 and the electro-magnet becomes de-energized, thereby permitting the return of contact 36 to its original or normal position by its spring carrier.

The application of stresses to the strips 32 at either side of the contact 36 insures positive pull down of the contact against the contact 37 and steady non-chattering engagement between the contacts during operation of the generator. Sparking is thus prevented resulting in long effective life of the contacts. Also, the design and arrangement is such that a greater magnetic flux in the core 15 is required to pull the contact 36 into engagement with the contact 37 than is required to hold them in contact. This relationship avoids chattering between contacts upon variations in the voltage developed by the generator. The movable contact carrier is so designed that the contact 36 is not pulled down until the voltage developed by the generator exceeds the battery voltage by a predetermined amount, and is held down at all generator volt-

ages between the pull-down voltage and the battery voltage, but is released when the generator voltage drops below the battery voltage. Thus, after the contact 36 has been once pulled down, non-chattering contact is maintained for all voltage variations which do not fall below the battery voltage. The armature at all times moves parallel to the axis of the core and stresses are equally and uniformly applied to the contact carrying member on both sides of the contact, thereby insuring accurate and proper action thereof. The lugs 34a engage the top insulator 20 to prevent contact of the armature with the head 19 of the core 15.

I claim:

1. In a circuit breaker, a stationary contact, a resilient member having fixed ends extending across said contact and being bowed into biased relation thereto, a second contact carried by said resilient member for cooperating with said first contact, a plate, and connections between said plate and resilient member for applying unbiasing stresses to the latter upon movement of the former.

2. In a circuit breaker, a stationary contact, a resilient member extending across said contact and being bowed into biased relation thereto, a second contact carried by said resilient member for cooperating with said first contact, a plate having an aperture in which said second contact is arranged, and connections between said plate and resilient member for applying unbiasing stresses to the latter upon movement of the former.

3. In a circuit breaker, a stationary contact, a resilient member extending across said contact and being bowed into biased relation thereto, a second contact carried by said resilient member for cooperating with said first contact, a plate and arms connecting intermediate points of said resilient member with said plate for applying unbiasing stresses to the former upon movement of the latter.

4. In a circuit breaker, a stationary contact, a resilient member extending across said contact and being bowed into biased relation thereto, a second contact carried by said resilient member for cooperating with said first contact, a plate having an aperture in which said second contact is arranged, and arms connecting intermediate points of said resilient member with said plate for applying unbiasing stresses to the former upon movement of the latter.

5. In a circuit breaker, a U-shaped frame, a stationary contact within said frame, a resilient member having its ends attached to the ends of said frame and being bowed into biased condition with respect to said stationary contact, a second contact carried by said resilient member for co-operation with said stationary contact, a plate, and connections between said plate and resilient member for applying unbiasing stresses to the latter upon movement of the former.

6. In a circuit breaker, a U-shaped frame, a stationary contact within said frame, a resilient member having its ends attached to the ends of said frame and being bowed into biased condition with respect to said stationary contact, a second contact carried by said resilient member for co-operation with said stationary contact, a plate, and arms connecting intermediate points of the resilient member with said plate for applying unbiasing stresses to the former upon movement of the latter.

7. In a circuit breaker, a stationary contact,

- 5 a resilient member extending across said contact and being bowed into biased relation thereto, a second contact carried by said resilient member for cooperation with said first contact, a plate and connections between said plate and resilient member for applying unbiasing stresses to the latter upon movement of the former, the extent of movement of said second contact being so limited that said resilient member retains its 10 condition of bias.
- 10 8. In a circuit breaker, a stationary contact, a plate, a pair of aligned spring tongues supported at their far ends and having their near ends attached to said plate, resilient members attached to both said tongues centrally and being laterally offset, and a second contact supported by said resilient members between the ends of said tongues for cooperation with said stationary contact, said resilient members being bowed into bias relation to said electro-magnet. 15
- 15 9. In a circuit breaker, a stationary contact, a second contact, a resilient member supporting said second contact, said member having fixed ends and being biased with respect to said first contact, a plate having an aperture through which said second contact is movable into engagement with said stationary contact, and connections between said plate and contact-carrying member for applying unbiasing stresses to 20 the latter upon movement of the former, said contact-carrying member requiring a greater stress to move said second contact into engagement with said first contact member than to hold said contacts together after engagement. 25
- 20 10. A device of the character described comprising a base, a U-shaped frame thereon, a contact supported within said frame, a second contact, a resilient carrier for said second contact extending between the ends of said frame, 30 said carrier having fixed ends and being biased with respect to said first contact, a plate having an aperture through which said second contact is movable into engagement with the first contact, and connections between said plate and contact 35 carrying member for applying unbiasing stresses to the latter upon movement of the former, said contact-carrying member requiring greater stress to effect engagement of the movable contact with the stationary contact than to maintain such engagement. 40
- 40 11. A device of the character described comprising a base, a U-shaped frame thereon, a contact supported within said frame, a second contact, a resilient carrier for said second contact 45 extending between the ends of said frame, said carrier having fixed ends and being biased with respect to said first contact, a plate having an aperture through which said second contact is movable into engagement with the first contact, and connections between said plate and contact carrying member for applying unbiasing stresses to the latter upon movement of the former. 50
- 50 12. In a switch, a stationary contact, a metal plate extending across said stationary contact, 55 said metal plate having an aperture, a bridge member integral with said plate and extending across the aperture, the length of the bridge member being greater than the length of the aperture, said bridge member being provided with two apertures separated by a transverse member integral with the bridge member, arms extending from the ends of the bridge member toward said transverse member, a second contact carried by said transverse member for co-operation with said stationary contact, and means for applying force to the free ends of said arms. 60
- 60 13. In a switch, a stationary contact, a metal plate extending across said stationary contact, 65 said metal plate having an aperture, a bridge member integral with said plate and extending across the aperture, the length of the bridge member being greater than the length of the aperture, said bridge member being provided with two apertures separated by a transverse member integral with the bridge member, arms extending from the ends of the bridge member toward said transverse member, a second contact carried by said transverse member for co-operation with said stationary contact, and a plate connected to the free ends of said arms for applying force thereto, said plate having an aperture in which said second contact is arranged. 70
- 70 14. In a switch, a stationary contact, a metal plate extending across said stationary contact, 75 said metal plate having an aperture, a bridge member integral with said plate and extending across the aperture, the length of the bridge member being greater than the length of the aperture, said bridge member comprising a second plate provided with two apertures separated by a transverse member integral with the plate, tongues integral with the first and second plates for supporting the latter from the former, arms extending from the ends of the second plate toward said transverse member, a second contact carried by said transverse member for co-operation with said stationary contact, and means for applying force to the free ends of said arms. 80
- 80 15. In a switch, a stationary contact, a metal plate extending across said stationary contact, 85 said metal plate having an aperture, a bridge member integral with said plate and extending across the aperture, the length of the bridge member being greater than the length of the aperture, said bridge member comprising a second plate provided with two apertures separated by a transverse member integral with the plate, tongues integral with the first and second plates for supporting the latter from the former, arms extending from the ends of the second plate toward said transverse member, a second contact carried by said transverse member for co-operation with said stationary contact, and a plate connected to the inner ends of said arms for applying force thereto, said plate being provided with an aperture in which said second contact is received. 90
